Primary Examiner — Mark A Goodwin(74) *Attorney, Agent, or Firm* — Baumgartner Patent Law; Marc Baumgartner(57) **CLAIM**

The ornamental design for a plow shank assembly, as shown and described.

DESCRIPTION

FIG. 1 is a left-side, bottom perspective view of a plow shank assembly embodying my new design;

FIG. 2 is a left-side view of the plow shank assembly of FIG. 1;

FIG. 3 is a right-side view of the plow shank assembly of FIG. 1;

FIG. 4 is a top view of the plow shank assembly of FIG. 1; FIG. 5 is a bottom view of the plow shank assembly of FIG. 1;

FIG. 6 is a front view of the plow shank assembly of FIG. 1; and,

FIG. 7 is a rear view of the plow shank assembly of FIG. 1. The broken lines show portions of the plow shank assembly that form no part of the claimed design.

1 Claim, 4 Drawing Sheets---
